CLAIM

The ornamental design for a contactless sensor unit for automatic door, as shown and described.

DESCRIPTION

FIG. 1 is a first perspective view of an embodiment of a contactless sensor unit for automatic door, showing our new design;

FIG. 2 is a second perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a cross-sectional view thereof, taken along line 9-9 of FIG. 3; and,

FIG. 10 is a cross-sectional view thereof, taken along line 10-10 of FIG. 3.
